UNITED STATES PATENT OFFICE.

HENRY O. SMEAD, OF NEWTON, KANSAS.

LUBRICATING JOURNAL-BOX.

1,121,302.

Specification of Letters Patent.

Patented Dec. 15, 1914.

Application filed June 28, 1913. Serial No. 776,220.

To all whom it may concern:

Be it known that I, HENRY O. SMEAD, citizen of the United States, residing at Newton, in the county of Harvey and State of Kansas, have invented certain new and useful Improvements in Lubricating Journal-Boxes, of which the following is a specification.

This invention relates to an improvement 10 in lubricating journal boxes.

The primary object of the invention is to provide a lubricating mechanism disposed within the journal box which will supply oil to the journal and which will continue 15 to lubricate the journal after the supply of oil in the box has been used.

A further object of the invention is to provide a structure which will convey the oil from the base of the box to the journal 20 and evenly distribute the same throughout the length of the journal.

A still further object of the invention is to provide an oil supplying member which will be resiliently supported in contact with 25 the journal and which may be conveniently renewed when the same becomes worn.

For a full understanding of the invention, reference is to be had to the following description and accompanying drawing, in 30 which:—

Figure 1 is a view showing a longitudinal sectional view of the box; Fig. 2 is a detail view of the lubricant supplying member, partially broken away to illustrate the interior construction of the same; Fig. 3 is a section taken transversely through the box, the upper portion of the box being broken away; Fig. 4 is a top view showing the manner in which the terminals of the shaft on 40 which the lubricant supplying roller is mounted are supported within their bearings; and Fig. 5 is an end elevation illustrating said mounting.

Corresponding and like parts are referred 45 to in the following description and indicated in all the views of the accompanying drawing by the same reference characters.

In the drawing, 10 designates the journal box which is of the usual construction and 50 which receives the journal 11 and the usual brass 12. Arranged in the base portion of the box adjacent each of its ends are supporting frames 13 and 14. These frames are substantially U-shaped and have their side 55 portions 15 bolted to the sides of the box, their base portions being formed with

flanges 16 which are bolted to the base of the box. Each of the frames is provided centrally with vertically extending guide arms 17 and 18 which are disposed in spaced relation, forming the guides for supporting blocks 19. The faces 20 of the arms are slotted as at 21 to receive the extensions 22 of the blocks, the blocks thus being supported against endwise movement. 60

A shaft 23 is supported by the blocks 22, the terminals of said shaft extending within the blocks. A spring 24 is interposed between the bases 25 of the frames and the blocks 19, whereby the blocks will normally 70 be maintained in raised position. A roller 26 is mounted on the shaft 23. This roller is provided with a series of longitudinally disposed channels 27, there being a packing of waste, asbestos or any shredded fiber 75 of an absorbent nature arranged in said channels, it being understood that the roller may be formed of metal, wood or fiber. The roller throughout its length is provided with spaced rows of apertures 29. The roller is 80 spaced from the base of the journal box and travels through the pool of oil, conveying the same to the journal and evenly distributing it throughout the length of the journal, it being understood that the oil is carried on the outer surface of the roller and 85 supplied to the journal.

It will be noted that as the roller travels through the oil, oil will pass through the openings 29 and saturate the packing 28. 90 The lubricant, which is supplied to the roller when the journal box is properly supplied with oil, is not fed from the packing but directly from the pool. When the supply of oil becomes exhausted in the pool 95 it will be seen that the oil will still be supplied to the journal, the oil being fed from the packing through the apertures 29. Thus even after the supply of oil in the journal box has been completely exhausted, 100 the journal will be lubricated. The longitudinal channels 27 are closed at the ends of the roller by concave disks 30 which are mounted on the shaft 23, the disks preventing the oil with which the material 28 105 becomes saturated from passing out through the ends of the channels 27. The ends of the roller are convex, whereby the concave plates may snugly embrace the same and prevent the material 28 from moving longitudinally of the roller. 110

The many advantages of a construction

2
of this character will be clearly apparent, as it will be noted that it provides, when the lubricant compartment is partly filled with oil, means for distributing the same quantity of oil at one end of the roller as at the other end and at the center. It will also be noted that after the supply of oil in the journal box has become exhausted, the journal will be lubricated by means 10 of the oil saturated material 28, and that the roller will be constantly maintained in contact with the journal by means of the springs 25. It will also be seen that the structure is such as may be easily and economically manufactured, and that it may 15 be placed within the journal box without altering its construction.

What I claim is:

A lubricating mechanism for journal 20 boxes including a roller mounted in the journal box and adapted to be immersed

in a lubricant contained in the journal box, said roller being formed with an annular series of longitudinally extending channels comprehended within its periphery, and absorbent material arranged within the channels, said roller being provided with a plurality of radially extending openings leading from the channels to the face of the roller, whereby the absorbent material 25 may absorb some of the lubricant in which the roller is normally immersed, and whereby the absorbent material will continue to supply a lubricant to the journal after the lubricant in the journal box has been totally consumed. 30

In testimony whereof I affix my signature in presence of two witnesses.

HENRY O. SMEAD. [L. s.]
